United States Patent Office.

C. W. TERPENING, OF GENESEO, ILLINOIS.

Letters Patent No. 93,768, dated August 17, 1869.

IMPROVEMENT IN CURD-GRINDERS.

The Schedule referred to in these Letters Patent and making part of the same.

To all whom it may concern:

Be it known that I, C. W. TERPENING, of Geneseo, in the county of Henry, and State of Illinois, have invented a new and improved Curd-Grinder; and I do hereby declare that the following is a full, clear, and exact description thereof, which will enable others skilled in the art to make and use the same, reference being had to the accompanying drawing, forming part of this specification, in which—

Figure 1 represents a vertical longitudinal section of my improved curd-grinder.

Figure 2 is a detail face view of one of its grinding-surfaces.

Figure 3 is a vertical transverse section of the same, taken on the plane of the line $x x$, fig. 1.

Similar letters of reference indicate corresponding parts.

My invention relates to machines for grinding curd, and mixing the same with salt; and

It consists in an improved arrangement and combination of parts for the accomplishment of said object, as hereinafter fully described.

A, in the drawing, represents a frame made of wood, or other suitable material, of two longitudinal side bars a , and a suitable number of cross-bars, b b .

This frame is to be fitted upon a vat, B, so that it can be firmly locked and readily removed. The cross-bar b at one end has, therefore, downward-projecting arms c with inwardly-projecting pins d that fit into the sides of the vat, while on the opposite end of the frame is a suitable wedge, key, set-screw, or cam, e , for locking the frame over the ends of the vat, as shown.

One of the end cross-bars b may be made adjustable longitudinally on the bars a , so as to adapt the frame to vats of different length.

C represents one of the grinding-disks. It is made of wood, or other non-corrosive material, and is mounted upon a wooden or other shaft, D, which has its bearings in one end cross-bar b of the frame, and in another movable cross-bar, b' , of the same. The shaft D can move with the bar b' , and slides then through the end cross-bar b .

E represents the other grinding-disk. It is fastened to a plate, f , which has a horizontal notch, whereby it is fitted upon a cross-bar b'' , of the frame A, a rubber

spring, g , being interposed between the front edge of the bar b'' and the plate f .

The disk E supports a hopper, F, and is on the sides and bottom surrounded by a forward-projecting flange, h , that embraces the disk C, as shown:

The lower end of the plate f is, by a rod, i , braced to a cross-bar, b' , of the frame.

Upon the faces of the disks C E are fitted the grinding-bars l , which may be alternately long and short, as shown, or of other suitable arrangement. They are bevelled to one side, and form sharp edges on the other.

When rotary motion in the right direction is, by hand or otherwise, applied to the shaft D, the bars of the two disks will be moved with the bevelled edges toward each other, and not with the sharp edges, as in ordinary mill-burrs.

It is not so much the object to cut the curd as it is to agitate and blend it with the salt.

The spring g allows the disk E to vibrate during the rotation of the disk C, so as to make the hopper self-feeding.

The prepared ground curd is discharged from the grinders through an aperture, m , of the disk E.

The curd to be treated is put into the hopper, and the shaft is then revolved, thereby grinding and mixing the contents of the hopper.

The flange h serves to retain the curd between the grinders as long as the same is not discharged through the aperture m .

The cross-bar b' can be adjusted more or less distant from the end of the frame, by means of wedges n , or otherwise, so as to hold the disks more or less close together.

Having thus described my invention,

What I claim as new, and desire to secure by Letters Patent, is—

The combination of the longitudinally-adjustable disk C, oscillating disk E, hopper F, flange h , and spring g , with the frame A, all constructed, arranged, and operating substantially as herein shown and described.

C. W. TERPENING.
